UNITED STATES PATENT OFFICE.

ARTHUR S. HIGGINS, OF NEW YORK, N. Y.

DESIGN FOR A JUG.

SPECIFICATION forming part of Design No. 25,387, dated April 14, 1896.

Application filed February 7, 1896. Serial No. 578,447. Term of patent 3½ years.

To all whom it may concern:

Be it known that I, ARTHUR S. HIGGINS, a citizen of the United States, residing at New York city, in the county and State of New York, have invented and produced a new and original Design for a Jug, of which the following is a specification, reference being had to the accompanying drawings, forming a part thereof, in which—

Figure 1 is a front elevation of a jug embodying the features of my design, and Fig. 2 is a perspective view of the same on a reduced scale.

In outline the body of the jug is substantially ovate and appears as emanating from a base, and at the top of the ovate body an irregular extension of the same appears. The surface of the representation of the jug, with

the exception of the base, has lines formed thereon, which lines are so assembled as to produce a representation of the figure of George Washington.

In detail the surface decoration of the jug is such as to represent the capped and cloaked figure of George Washington, the cloak being thrown open to disclose a portion of the person, the figure being also represented as holding a sword in one hand.

I claim—

The design for a jug, substantially as herein shown and described.

ARTHUR S. HIGGINS.
